3 Claims. (Cl. 239—417.3)

ABSTRACT OF THE DISCLOSURE

Apparatus particularly adapted for recovering crystallized material ejected from an aspiration nozzle confined in a housing in which pressurized air is directed through an outer rigid conduit and coaxially around an inner feed pipe having a coaxial insulating chamber formed by a coaxial plastic inner hose, in which a tubular nozzle element threadedly engages in the plastic inner hose and is confined by a rigid ring circumposed about the hose within the end of the feed pipe, and the nozzle element includes radial openings disposed above a reduced diameter outlet at the terminal end of the outer conduit.

This invention relates to an aspiration gun and, more particularly, to an aspiration assembly or gun for use in ejecting flowable materials to be crystallized into a crystallization chamber.

It is an object of this invention to provide an aspiration gun for flowable materials of low or high solid content to recrystallize or dry, by aspiration at a high temperature or a low temperature, the said solids.

It is another object of this invention to provide an aspiration gun of the type described hereinafter which includes a main tubular portion having an ejector end and an inlet end and with a throat adjacent the ejector end to eject an annular stream of high velocity air and a feeder tube disposed coaxially in the portion having a nozzle at the ejector end to expel liquids carrying material to be crystallized into the annular stream.

Another object of this invention is to provide a device of the type described generally in the preceding paragraph and more particularly hereinafter wherein the said feeder tube includes an insulation jacket circumposed thereabout and confined by an outside tube around an inside tube.

Another object of this invention is to provide a device of the type described hereinafter having its parts arranged, constructed and adapted as set forth hereinafter for the purposes specified which is simple and inexpensive to operate and is composed of parts which are adapted for assembly in an inexpensive manner and which may be disassembled for cleaning purposes.

In accordance with these and other objects which will become apparent hereinafter, the instant invention will now be described with reference to the accompanying drawings illustrating a preferred embodiment thereof.

In the drawings:

FIGURE 1 is a partial elevation view which is partly in cross section to illustrate the operation of the instant assembly;

FIGURE 2 is a side elevation view of the gun which has been partly broken away for purposes of illustration;

FIGURE 3 is a view in cross section taken along the plane indicated by the line 3—3 of FIGURE 2 and looking in the direction of the arrows;

FIGURE 4 is a partial elevation view which has been broken away illustrating the upper left-hand portion of FIGURE 2 in cross section;

FIGURE 5 is a cross-sectional view taken along the

2

plane indicated by the line 5—5 of FIGURE 4 and looking in the direction of the arrows;

FIGURE 6 is a top plan view of FIGURE 4;

FIGURE 7 is an enlarged elevation view of the nozzle 5 at the upper end of FIGURE 4;

FIGURE 8 is an enlarged view in cross section of the nozzle 5 at the upper end of FIGURE 4; and

FIGURE 9 is a view in cross section taken along the plane indicated by the line 9—9 of FIGURE 8 and looking in the direction of the arrows.

Referring to the drawings, wherein like reference characters designate like or corresponding parts throughout the different views, and referring particularly to FIGURE 1, the numeral 1 generally designates an injector means or aspiration gun to introduce material from one end of the gun into the main chamber of the housing 13 in droplet or particle form carried on a stream of high velocity gas, such as air, to be crystallized. The other end of the gun 1 is connected to a source 14 of high velocity air, such as the fan 14. The gun, when so connected, comprises a conduit through which a gas current may flow to the gun outlet in circumposed relation of the co-axially arranged nozzle means 5. The product to be crystallized is delivered to the gun through a suitable pipe, such as that designated by the numeral 17, which includes regulating means such as the valve 18. The said pipe means 17 is connected to the gun. The hose 6 which is of flexible material is provided to connect the gun 1 to the delivery side of the fan 14 and a threaded coupling 7 is adapted to connect the gun to the hose 6, whereby cleaning and adjusting procedures may be conducted with respect to the aspiration gun. The aspiration gun comprises, as can be seen in FIGURE 2, a curved tube or pipe which is dimensioned in accordance with the particular installation 25 in which it is used. The injector end of the gun is provided with a throat of reduced cross-sectional area to increase the velocity of the gas on ejection therefrom. In coaxial arrangement and extending through the substantial length of the gun shown there is disposed a feeder tube 2 which by reason of its coaxial relation with the gun follows the contour thereof and because it is of a smaller diameter than the gun diameter in size, is separated from the inside wall of the gun and held in coaxial relation by spacers 4 arranged interiorly along the length of the gun. Inside of 30 the feeder tube 2 there is disposed, also in coaxial relation with the gun and, consequently, the feeder tube, an inside hose 15 which is of a suitable, flexible plastic material and is adapted to conduct a solution or flowable mixture to be crystallized to the aspiration gun outlet.

The aspiration air supply flows within the circumposed space 3 around the feeder tube 2 and past the nozzle 5 in a stream which is apparent on inspection of FIGURE 4 and which will be explained hereinafter. The inside hose, it will be noted, terminates substantially at and slightly inside of the delivery end of the feeder tube 2 and is arranged to expel flowable material through the radial orifices 9 with which it is provided. The aspiration is caused by the liquid expelled through the orifices 9 being entrained by the high velocity stream of air from the nozzle passing through the space 3. As seen in FIGURE 3, the other end of the feeder tube and the coaxial inside hose 15 are connected to the pipe 17 which controls the flow of flowable materials from a source by means of the valve 18 and to the inlet side of the gun. 45 Also, the threaded section on the coupling 7 adapts it for connection with mating threads on the flexible hose 6 50 which connects to the fan 14. Referring to FIGURE 4, the aspiration nozzle 5 is connected to the plastic hose 15 as by the threads 10. A holding ring 8 may be provided to hold and grip the hose to the threaded projecting por-

tion of the nozzle 5, and the said ring may be utilized as a spacer to maintain the coaxial relation of the feeder tube 2 and inside hose 15 with the air space 16 therebetween being of assistance in cooling hot flowable materials to be atomized. The nozzle and feeder tube are held in substantially the relative relation with respect to the gun body shown in FIGURE 4 by means of the spacer 4 so that the main stream of air flow through the space 3 is around the nozzle and in this way aspirates the materials expelled through the orifices 9. It will be apparent that the 10 nozzle includes a bore 11 or chamber which connects with and is a continuation inside hose interior to flow the materials to the lateral openings 9. The numeral 12 indicates two orifices or holes which are useful for detachably connecting the nozzle in the gun. 15

In the preferred embodiment, the outside tube is of rigid material and operates as a guide tube for the inside tube so that it may be removed and inserted readily and without disturbing the relative coaxial positioning arrangement of the feeder tube in chief with respect to the gun. 20

While the instant invention has been shown and described herein in what is conceived to be the most practical and preferred embodiment, it is recognized that departures may be made therefrom within the scope of the invention, which is therefore not to be limited to the details disclosed herein but is to be accorded the full scope of the claims so as to embrace any and all equivalent apparatus and articles.

What is claimed is:

1. Apparatus for collecting material to be crystallized comprising, in combination: a vertical housing for confining crystallized material; an aspirator assembly (1) supported on said housing and comprising nozzle means extending upwardly into said housing; means (14) for supplying high pressure air exteriorally of said housing and including an outlet conduit connected to said gun, 35 said gun comprising a rigid tubular conduit connected at one end of said outlet conduit and projecting laterally into said housing and terminating at said nozzle means, said rigid conduit including a reduced diameter open end merging into a larger diameter portion therebelow whereby increased velocity air is expelled from 45 said open end, feed pipe means extending axially into said rigid tubu-

lar conduit and supported in coaxial relation therein and terminating at said nozzle means,

said feed pipe means comprising a rigid outer tube and an inner plastic hose disposed in spaced relation from the inner surface of said rigid outer tube and defining an annular coaxial insulation space therebetween, an annular, rigid, ring circumscribed about said plastic hose adjacent said nozzle means and disposed within said rigid outer tube,

said nozzle means comprising a tubular, externally-threaded portion engaged within said plastic hose and confined thereto by said annular ring, said tubular portion including an axial bore (11) communicating with radial orifice portions spaced above the open end of said reduced diameter portion of said rigid conduit, said tubular portions including an annular flange, below said radial orifices and clamping engaging the terminal ends of said feed pipe rigid tubular conduit and said plastic hose at said rigid ring.

2. The structure as claimed in claim 1 in which said feed pipe includes intermediate control valve means exteriorally of said housing for metering the flow of material therethrough.

3. The structure as claimed in claim 1 in which said rigid tubular conduit includes a detachable, flexible coupling section exteriorally of said housing for facilitating maintenance and repair.
